BALL VALVE

Robert Clade, Detroit, Mich., assignor to American Car and Foundry Company, New York, N. Y., a corporation of New Jersey

Application April 25, 1952, Serial No. 19,484

Term of patent 14 years

(Cl. D78—1)

To all whom it may concern:

Be it known that I, Robert Clade, a citizen of the United States, residing at Detroit, State of Michigan, have invented a new, original, and ornamental Design for Ball Valve, of which the following is a specification, reference being had to the accompanying drawing, forming a part hereof.

Fig. 1 is a side elevational view of the ball valve embodying my design.

Fig. 2 is a plan view of the ball valve and looking toward the stem end.

Fig. 3 is an end elevational view of the ball valve.

I claim:

The ornamental design for a ball valve substantially as shown.
